UNITED STATES PATENT OFFICE.

ARDEN CAMERON, OF NORWICH, ONTARIO, CANADA.

DITCHING MACHINE.

1,424,151.

Specification of Letters Patent. Patented Aug. 1, 1922.

Application filed July 29, 1920. Serial No. 399,727.

To all whom it may concern:

Be it known that I, ARDEN CAMERON, of Norwich, in the county of Oxford, Province of Ontario, Canada, a subject of the King 5 of Great Britain, have invented certain new and useful Improvements in Ditching Machines, of which the following is a specification.

This invention relates to machines for 10 digging trenches in which to lay drain tiles, and my object is to devise effective means for performing the actual operation of digging and also to provide means for elevating and carrying away the dirt automatically 15 adjustable to follow the digging apparatus as the trench increases in depth.

The machine is hereinafter more particularly described and illustrated in the accompanying drawings in which

20 Fig. 1 is a side elevation of my improved ditching machine;

Fig. 2 a rear elevation of the digger;

Fig. 3 a plan view of the machine; and

Fig. 4 a vertical section of the digger.

25 In the drawings like numerals of reference indicate corresponding parts in the different figures.

1 is the frame of a machine suitably shaped to support the different parts. This 30 frame is supported on the rear ground wheels 2 and the front ground wheels 3, the front wheels being mounted in any ordinary way to enable the machine to be steered. At the forward part of the frame is supported a guide 4, in which slides the digger arm 5. At the lower end of the digger arm 35 is secured the digger 6 constructed as hereinafter described. The digger arm is raised and lowered in its guide by means of a windlass 7 of any ordinary construction. The 40 frame is provided with a superstructure 8, which braces the guide 4 and also the upper ends of the weight boxes 9.

10 is an elevator deck formed in two 45 parts, hinged together at 11 and hinged at its front and rear ends respectively at 12 and 13 to the digger and to the frame of the machine. It is evident from this arrangement that the deck will readily accommodate 50 itself to the various positions of the digger as the latter is lowered in the trench being dug. The weight of the elevator deck and its load is counterbalanced by the weights 55 14 which slide in the weight boxes 9 and are connected by cables 15 passing over guiding

sheaves 16 connected with the opposite sides of the elevator deck adjacent the hinge 11.

Running on the elevator deck is an endless elevator conveyor 17 of any suitable type. The rear end of this conveyor runs 60 on sprocket wheels 18 fast on the shaft 19 journalled behind the axle 20 of the rear ground wheels 2. This shaft 19 forms the pin of the hinge 13 for the elevator deck. The shaft is driven by spur gearing 21 from 65 one of the rear ground wheels.

The elevator delivers to a laterally directed endless conveyor 22 of any ordinary type, which is suitably supported on the frame work and is driven by means of the 70 diagonal shaft 23 driven by bevel gearing 24 from one of the rear ground wheels 2. The shaft 23, it will be seen, extends in front of the axle 20, thus bringing the laterally directed conveyor into proper position to 75 receive dirt delivered from the elevator conveyor.

The digger 6 is constructed as follows. The pin of the hinge 12 between the elevator deck 10 and the digger is preferably formed 80 by the spindle of a roller 25 round which passes the elevator conveyor 17, which will be provided with side chains running on the sprocket wheels 26 connected with the spindle of the roller 25. This journal is 85 spaced between the side pieces 27 of the digger, the upper ends of these side pieces being shaped to form between them a socket 28 in which the lower end of the digger arm 5 is secured. Outside the side pieces 27 are 90 secured the land sides 29, while to their forward ends is secured the digger point 30, the upper surface of which is upwardly inclined as shown. A brace provided with lugs is secured to the side pieces and to the 95 digger point to brace and connect the same.

The digger is provided with two rolling colters 31, one at each side projecting below the bottom of the land sides. These colters are preferably secured to independent shafts 100 32 independently journalled in the land sides and a bent brace 33 connecting the side pieces 27.

Supported between the side pieces 27 is a short slat conveyor 34 running over the rollers 35-36, so positioned that the short conveyor will receive dirt from the digger point and deliver it on top of the elevator conveyor 17. This conveyor is provided with a single sprocket chain running on the sprocket 110

wheels 37 on the spindles of the rollers 35 and 36. An inclined deck 38 is secured between the side pieces 27 supporting the upper side of the conveyor between the rollers 35 and 36. To protect the under side of the conveyor I secure between the side pieces 27 the inclined guard 39 located just below the roller 35. By means of gearing 40 at each side, the roller 36 is driven from the roller 5. 10 This gearing is located outside the side pieces 27 and is covered by the gear boxes 41 secured to the side pieces. As these gear boxes project, it is necessary to provide means for slightly widening the trench at this point to 15 provide room for the passage of these gear boxes. I therefore provide the skimmers 42 of a type well known in the art, which have their stems 43 secured to the side pieces 27 by clamps 44. 20 The operation of the device is as follows. First of all, by means of a farm plow, a shallow furrow is opened the entire length of the drain to be dug, returning in the same furrow. If the surface of the earth is uneven, 25 it is better to scrape the edges of the furrow back each way with a log scraper to make a more uniform surface on which the ground wheels may travel. The digger is then lowered into the furrow and the machine drawn 30 forward by any suitable tractive power, approximately at a speed of two to two and one-half miles per hour. The point of the digger scrapes out the bottom of the furrow to a depth of cut of approximately two 35 inches. The earth is forced back over the inclined top of the point and is received by the short conveyor 34, which carries it rearwardly and deposits it on the elevator conveyor 17, which carries it back and deposits it on 40 the laterally directed conveyor 22 which deposits it well to one side of the machine.

On arriving at the end of the trench, the digger is raised by means of the windlass 7 and the machine turned and run back through 45 the trench making another 2" cut. The process is repeated until the desired depth is obtained.

In finishing the bottom of the drain in readiness to receive the drain tile, the rolling 50 colters 31 are removed and the straight digger point 30 removed and replaced by a special concave point which will form a clean concave bottom to the drain.

What I claim as my invention is:—

55 1. Ditching apparatus comprising a wheeled frame; a vertically adjustable digger supported by the frame; an elevator deck formed in two parts hinged together, the forward end of the forward part being hinged on 60 the digger and the rearward end of the other part on the frame; yielding means tending to raise the elevator deck intermediate of its

ends; and an endless conveyor carried by said deck.

2. Ditching apparatus comprising a wheeled 65 frame; a vertically adjustable digger supported by the frame; an elevator deck formed in two parts hinged together, the forward end of the forward part being hinged on the digger and the rearward end 70 of the other part on the frame; cables connected to the elevator deck; guides over which said cables are led; weights connected to the cables tending to raise the elevator deck; and an endless conveyor carried by 75 said deck.

3. A ditching machine constructed as set forth in claim 1 provided with an upwardly inclined digger point; a short endless conveyor on to which the digger point delivers, 80 the conveyor in turn delivering on to the elevator conveyor; and gearing driving the short conveyor from the elevator conveyor.

4. A ditching machine constructed as set forth in claim 1 provided with an upwardly 85 inclined digger point; a short endless conveyor on to which the digger point delivers, the conveyor in turn delivering on to the elevator conveyor; gearing driving the short conveyor from the elevator conveyor; gear 90 boxes covering the gearing and projecting beyond the sides of the digger; and skimmers secured to the sides of the digger adapted to cut away the sides of the trench to afford passage for the gear boxes. 95

5. In a ditching machine, a digger provided with spaced landsides; a digger point with upwardly inclined upper surface; and a short endless conveyor located between the landsides, its upper side forming substantially an upward extension of said surface; an endless elevator conveyor, the lower end of which is supported between the landsides of the digger below the rear end of the short conveyor. 100

6. A ditching machine constructed as set forth in claim 5 provided with a roller for the forward end of an elevator conveyor located below the rear end of the short conveyor; gearing outside the land sides between said roller and the rear end of the short conveyor; gear boxes over said gearing; and skimmers secured to the sides of the digger adapted to cut away the sides of the trench to afford passage for the gear boxes. 110 115

7. In a ditching machine, a digger comprising an open frame; landsides secured thereto; a digger point secured thereto; and rolling colters supported one at each side and projecting below the bottom of the landsides. 120

Signed at Norwich this 14th day of July, 1920.

ARDEN CAMERON.
